UNITED STATES PATENT OFFICE.

CASSRIL VINEGRAD, OF KINGSTON-UPON-HULL, ENGLAND.

TABLE FOR ATTACHMENT TO SEATS, DESKS, AND OTHER ARTICLES.

Application filed July 13, 1925, Serial No. 43,178, and in Great Britain July 22, 1924.

This invention relates to tables for application to chairs, desks and other articles.

It is the purpose of this invention to provide a table which can be quickly and easily applied to and removed from chairs and in particular what are known as easy chairs, settees, desks and other articles and which, when fitted, will hang down and lie parallel or almost so with one side or arm, or it may be the back of the chair, settee, desk or the like, when not required to be used, but can, by a simple action, be raised and supported in its raised position and if desired, swung around to the front of the chair, settee, desk or the like if it is mounted on one arm or side thereof, or swung around to one side of the chair, settee, desk or the like if it is mounted on the back thereof.

With the above and other purposes in view the invention consists in the details of construction and in the arrangement and combination of parts hereinafter described.

In the accompanying drawings there is shown by way of example an easy chair provided at one side with my invention.

In the drawings, Fig. 1 is a perspective view of an easy chair with the table embodying this invention applied to one side thereof, the table being shown in its raised position for use.

Fig. 2 is a front view of a portion of the chair showing the table in its raised position for use, the dotted lines showing the table hanging down in its out-of-use position.

Fig. 3 is a side view of a portion of the chair showing the table in its raised position for use.

Fig. 4 is a similar view to Fig. 3 but shows the table hanging down in its out-of-use position, a portion of such table being broken away to allow of a portion of the supporting rod behind, being seen, and Fig. 5 is a plan view of the chair showing the table in its raised position for use, the dotted lines at the front of the chair showing the table swung round to the front of the chair.

Figs. 2, 3 and 4 are drawn to a larger scale than Fig. 1; and Fig. 5 is drawn to a smaller scale than Fig. 1.

The same reference numerals are employed to indicate the same or like parts in the several figures of the drawings.

Referring to the drawings, 1 indicates the chair, 2 and 3 are two tubes attached to or formed integral with two plates 4 and 5, the said tubes being secured to the outer face of

one side of the chair by screws 6 which pass through screw holes in the plates of the tubes and are screwed into the side of the chair.

7 is a horizontal rod having a suitably long downwardly extending leg 8 at its inner end which leg passes through the tubes 2 and 3 secured to the side of the chair and is rotatable therein whereby the horizontal rod is adapted to have a swivelling movement, and 9 is a fixed collar on the leg 8 and which rests on the top of the tube 2 and supports the leg 8 and the horizontal rod 7 at the required height.

10 is the table which may be of wood, 70 papier-mâché or other suitably strong material, and 11 and 12 are two tubes attached to or formed integral with two plates 13 and 14, the said tubes being secured to the underside of the table at or near the inner edge thereof by screws 15 which pass through screw holes in the plates of the tubes and are screwed into the underside of the table, the said tubes 11 and 12 being passed on to the horizontal rod 7 on which they are rotatable and so allow of the table swinging on such rod 7.

16 is an inclined stay rod the lower end of which is provided with a collar 17 which is arranged on the leg 8 of the horizontal rod 7 and the top end of which is secured to the said horizontal rod by means of a set screw 18.

19 is a rod loosely mounted on the stay rod 16 by means of a sleeve 20 provided with a socket 21 in which the bottom end of the said rod 19 is fitted, 22 being a fixed collar on the stay rod 16 which prevents the sleeve 20 provided with the rod 19 from sliding down the stay rod 16.

23 is a helical spring arranged on the stay rod 16 one end of which spring is suitably connected to the sleeve 20 as for example, by a set screw 24 screwed into the socket 21 of such sleeve, the other end of such spring being connected to the stay rod by any suitable means, as for example by a set screw 25 screwed into the said stay rod.

The rod 19 forms the support for the table 10 when such table is raised for use, the outer end of which rod bears against the inner face of an inclined or curved stop 26 with which the underside of the table is provided and which prevents the said rod from being depressed against the tension of the spring 23 which automatically raises such supporting rod when the table is raised.

The table when not required for use hangs down vertically, or almost vertically as shown in Fig. 4 and in dotted lines in Fig. 2, the supporting rod 19 being pressed downwardly by the weight of the table, the spring 23 yielding to allow of this.

When it is required to use the table it is turned up on the horizontal rod 7, the supporting rod 19 being raised at the same time by the tension of the spring 23. The outer end of the supporting rod is then arranged behind the stop 26 on the underside of the table and the table is then ready for use and can be used either at the side of the chair as shown in Figs. 1, 2, 3 and 5 or be swung around to the front thereof as shown in dotted lines in Fig. 5.

Although I have described tubes as the means for receiving the leg or stem of the horizontal rod which carries the table and in which such leg is adapted to turn, and I have also described tubes secured to the underside of the table as the means whereby the table is mounted on the horizontal rod 25 and is adapted to turn thereon, it will be obvious that I may employ strong screw-eyes to screw into the side or back of the chair or other article to which the table is to be applied and into the underside of the table in substitution for such tubes, or that I may secure metal plates or strips each having one end bent into an eye, to the chair or other article and to the underside of the table, for the purposes mentioned.

Furthermore, I may if desired, make the table of metal and form the eyes for mounting the table on the horizontal rod, integral with the table.

What I claim and desire to secure by Letters Patent is:—

1. The combination with an article of furniture, of bearings carried by said article, a support comprising a cylindrical vertical leg mounted in said bearings to turn therein, a stop fixedly mounted on said leg for limiting the downward movement of said leg in said bearings, an integral cylindrical arm extending horizontally from said leg, an inclined rod extending between said leg and arm and fixed in relation thereto, a table, bearings carried by said table and receiving said arm whereby said table may swing about said arm to folded or raised position, a supporting rod loosely mounted on said inclined rod to swing about the same, a stop on said in-

clined rod limiting the movement thereon of said swinging supporting arm toward said leg, resilient means tending to swing said supporting arm upward toward said table, and a stop on the opposed face of said table to be engaged by the adjacent end of said supporting rod when said supporting rod and table are in raised position. 60

2. The combination with an article of furniture, of bearings carried by said article, a support comprising a vertical leg mounted in said bearings, a stop fixedly mounted on said leg for limiting the downward movement of said leg in said bearings, an integral arm extending horizontally from said leg, an inclined rod extending between said leg and arm and fixed in relation thereto, a table, bearings carried by said table and receiving said arm whereby said table may swing about said arm to folded or raised position, a supporting rod loosely mounted on said inclined rod to swing about the same, a stop on said inclined rod limiting the movement thereon of said swinging supporting arm toward said leg, resilient means tending to swing said supporting arm upward toward said table, and a stop on the opposed face of said table to be engaged by the adjacent end of said supporting rod when said supporting rod and table are in raised position. 70

3. The combination with an article of furniture, of bearings carried by said article, a support comprising a vertical leg mounted in said bearings to turn therein, an integral arm extending horizontally from said leg, an inclined rod extending between said leg and arm and fixed in relation thereto, a table, bearings carried by said table and receiving said arm whereby said table may swing about said arm to folded or raised position, 90 a supporting rod loosely mounted on inclined rod to swing about the same, means limiting the movement of said supporting rod endwise of said inclined rod, resilient means tending to swing said supporting rod upward toward said table, and a stop on the opposed face of said table to be engaged by the adjacent end of said supporting rod when said supporting rod and table are in raised position. 100

In testimony whereof, I have signed my name to this specification at Kingston-upon-Hull, England, this second day of July, 1925.

CASSRIL VINEGRAD.
